United States Patent Office

Des. 195,901
Patented Aug. 6, 1963

195,901

BOTTLE OR SIMILAR ARTICLE

Alfred D. Sterges, Los Angeles, Calif., assignor to Purex Corporation, Ltd., Lakewood, Calif., a corporation of California

Filed Aug. 20, 1962, Ser. No. 71,344

Term of patent 14 years

(Cl. D58—8)

FIG. 1.

FIG. 2.

FIG. 3.

FIG. 1 is a side elevational view of a bottle embodying my new design;

FIG. 2 is a top plan view of FIG. 1; and

FIG. 3 is an enlarged fragmentary cross section taken on line 3—3 of FIG. 1.

The dominant features of my design reside in the portions shown in full line.

I claim:

The ornamental design for a bottle or similar article, substantially as shown and described.
